BROACHING MACHINE

Edgar D. Vancil and Amos H. Hawley, Sr., Cincinnati, Ohio, assignors to The Cincinnati Milling Machine Company, Cincinnati, Ohio, a corporation of Ohio

Application May 22, 1937, Serial No. 144,192

18 Claims. (Cl. 90—33)

This invention relates to improvements in automatic broaching machines.

One of the objects of this invention is to provide an automatic broaching machine having improved work translating and positioning means.

Another object of this invention is to provide an improved automatic single ram broaching machine.

10 A further object of this invention is to provide an improved hydraulic operating and control circuit for automatic broaching machines.

Other objects and advantages of the present invention should be readily apparent by reference 15 to the following specification considered in conjunction with the accompanying drawings illustrative of one embodiment thereof, but it will be understood that any modifications may be made in the specific structural details within the scope 20 of the appended claims without departing from or exceeding the spirit of the invention.

Referring to the drawings in which like reference numerals indicate like or similar parts:

Figure 1 is an elevation of a broaching machine embodying the principles of this invention.

Figure 2 is an elevation of the machine shown in Figure 1 as viewed from the right end of that figure.

Figure 3 is an enlarged sectional view taken 30 on the line 3—3 of Figure 1 and showing the details of the table operating mechanism.

Figure 4 is an enlarged view taken on the line 4—4 of Figure 1, with certain portions in section, showing the trip controlled mechanism 35 operated by the table.

Figure 5 is a diagrammatic view of the hydraulic control circuit.

Referring to Figures 1 and 2 of the drawings, the reference numeral 10 indicates the column 40 of a broaching machine, upon which is slidably mounted in suitably formed guideways, a broaching ram 11, which is adapted to have a series of broaching tools attached thereto for movement relative to a work supporting table 12.

45 The ram 11 has a cylinder 13 integrally formed therewith, and contained in this cylinder is a piston 14 which is connected by a double tubular piston rod 15 to a fixed part 16 of the machine. By means of this arrangement the cylinder is the moving element, and the piston, the fixed element. By means of the double tubular piston rod it is possible to cause fluid to flow between the inside tube 17 and the outside tube 18 to the upper end 19 of the cylinder, the outside 50 sleeve having radial holes or passages 20 drilled

therein near one face of the piston. The inner tube 17 serves to convey fluid to the lower end 21 of the cylinder. The tube 17 is connected by a channel 22 to port 23 of the ram controlled valve; and the annular space between the tubes is connected by a channel 24 to port 25 of the ram controlled valve 26. It should be apparent that by alternately admitting fluid to channels 22 and 24 and connecting the remaining channel to reservoir that the broaching ram may be 10 caused to move up and down.

The table 12 is supported on horizontal guideways 27 as more particularly shown in Figure 2, for movement in a plane at right angles to the plane of movement of the broaching ram. In 15 other words, while the broaching ram is at the upper limit of its stroke, the table 12 may be advanced to position a work piece in the path of the broaching tools and while held in a prescribed position, the broaching ram may be 20 moved downward to effect a cutting operation. After the operation has been completed, the table 12 is returned to move the work out of the path of the broaching tools, and the ram itself is raised to its starting position.

25 Means have been provided whereby the table 12 is advanced and retracted automatically with respect to some prescribed working position so that the operator's duties are reduced to simply loading and unloading the machine, and starting 30 the machine after each cycle if the machine is operating on the single cycle method.

To this end the table has integrally formed therewith, as shown in Figures 3 and 5, a cylinder 28, and this cylinder contains a piston 29 35 which is connected by a double tubular piston rod 30 to a fixed part 31 of the machine. The piston rod has an inside tube 32 through which fluid is admitted to one end 33 of the cylinder to cause advance of the table to a broaching position; and an annular space 34 between the inner tube and the outside tube 35 for admitting fluid to the other end 36 of the cylinder for causing retraction of the table.

40 As shown in Figure 3, the piston rod 30 has a lost motion connection with the fixed part 31 of the machine. In other words, the extreme end of the piston rod is provided with an enlarged head 37 which forms a shoulder 38 engageable with one side 39 of an abutment portion 40. The purpose of the lost motion connection is to make 50 possible the automatic positioning of a locking lever 41 after the work table has moved into cutting position; and the automatic withdrawal of the lever before the table returns.

The lever 41 is part of a bell crank 42 which has a second arm 43, the end of which is bifurcated, as more particularly shown in Figure 4, for engagement with slots 44 cut in opposite sides of a block 45 integral with the piston rod. In the position of the parts shown in Figure 3, the work table 12 is in a cutting position and the lever 41 is in a locking position. It will be evident that upon admission of fluid pressure to the chamber 36 of cylinder 28 that the piston 29 will move toward the right until the lost motion existing between the head 31 and the shoulder 39 is taken up. This movement will be sufficient to rotate the bell crank clockwise through a sufficient angle to cause the end of the lever 41 to clear the abutment 46 which is integral with the table. With the locking lever withdrawn and the piston 29 held against further movement by the abutment 39, the fluid pressure is now able to cause retraction of the table 12.

Upon reversal of pressure in cylinder 28, or in other words, upon admittance of fluid pressure to chamber 33 of the cylinder, the piston 29 will be urged toward the left as viewed in Figure 3 because it is freer to move than the table, but this movement will be prevented to a large extent for the present because the abutment 46 is now positioned over the top of the lever 41 having been moved to that position when the table 12 was retracted. Since the piston 29 is thus restrained against movement the table 12 will be advanced and the abutment 46 will ride along the top of the lever 41. When it clears the end, the lever 41 moves into locking position thereby creating the space between the shoulder 38 and 39. The table is prevented from moving further ahead by adjustable positive stop means. In other words, the column of the machine is provided with a pair of spaced abutments 47 which are in line with a pair of adjustable stops 48 carried by the table. Each of these adjustable stops consists of a bolt 49 which is threaded into the end of the table and locked in position by a lock nut 50. It will now be apparent that pressure in the chamber 33 is urging the table forward against the positive stops which react in such a way as to cause the piston 29 to move toward the left and thereby urge the bell crank in a counterclockwise direction into locking position until the angular surface 51 on the abutment 46 prevents further rotation of the bell crank. The table is thus locked against movement in either direction.

The block 45 forming part of the piston rod has a depending portion 52 through which two holes are drilled forming part of channels 53 and 54 by which the cylinder is connected to the control valve. It will be noted that the channel 53 in Figure 3 terminates in an angular portion which intersects the annular space 34 existing between the outside tube 35 and the inside tube 32. Since this annular space does not continue through the block 45, the channel 54 may continue straight whereby it will intersect an annular groove 55 formed in the block as more particularly shown in Figure 4. The end of the inside tube 32 is provided with drilled holes 56 adjacent this portion to effect hydraulic connection to the inside of tube 32.

Although the block 45 and the dependent portion 52 are rigid with the piston rod and move with it, metal tubes can still be utilized to form the connecting portions of channels 53 and 54 with the control valves by forming the connecting tubular portions in the shape of a U.

The channel 53 terminates in port 57 of the

ram controlled valve 26, and the channel 54 terminates in two ports, one of them being port 58 of the ram controlled valve and the other being port 59 of the table controlled valve 60.

The plunger 61 of the ram controlled valve is shifted by hydraulic pressure under the control of a pilot valve 62. This pilot valve has a shiftable plunger 63 which has two positions and is normally held in either one of these two positions by a spring pressed detent 64 engageable with 10 detent notches 65 cut in the periphery of the plunger. This valve has a pressure port 66 which is supplied with fluid by a constant displacement or metering pump 67 through channel 68. It also has a pair of ports 69 and 70 which are connected by channels 71 and 72 respectively to opposite ends of the valve housing 26. An additional pair of ports 73 and 74 of the pilot valve are connected to the exhaust or return line 15 which has a low pressure check valve 76 therein 20 for maintaining the lines full of fluid. It will be noted that a central spool 78 formed on the plunger 63 is larger in diameter than the shoulders 77 and 79, whereby the valve becomes a self-actuating valve. In other words, after the spool 25 78 passes pressure port 66, the fluid entering the annular groove on either side of the spool will produce unequal resultant pressures axially of the valve plunger and will continue the movement of the plunger in the direction in which it 30 is moving thereby operating in the manner of a load-and-fire mechanism.

The plunger 63 is shifted by dogs carried by the broaching ram, and to this end the plunger is provided with an enlarged head 80 which has 35 annular beveled surfaces 81 and 82 formed on opposite sides thereof. A trip dog 83 carried by the ram has a V-shaped projecting head 84 which is adapted to engage the beveled surface 82 on the head of the plunger to shift the same to the left as viewed in Figure 5. The ram also carries a second dog 85 which has a V-shaped head engageable with a beveled surface on the end of the plunger for shifting the same toward the right as viewed in Figure 5. Thus the pilot valve is 40 shifted from one extreme position to the other at each end of the stroke of the broaching ram.

The valve plunger 86 of the table controlled valve 60 is also hydraulically shifted and this shifting is under the control of a second pilot 50 valve 87 having a plunger 88. This plunger has an enlarged central spool 89 on the opposite sides of which are annular grooves 90 and 91 which terminate in shoulders 92 and 93 respectively which, as shown in the drawings, are smaller in 55 diameter than the spool 89 whereby the valve becomes a self actuating valve. The valve 87 is provided with a pressure port 94 which is supplied with fluid from the pump 68 through a branch 95 of channel 68. On opposite sides of 60 the pressure ports are a pair of ports 96 and 97 which are connected by channels 98 and 99 respectively to opposite ends of the table controlled valve 60. In addition, a pair of exhaust ports 100 and 101 formed in the pilot valve are 65 connected by branch 102 to the return line 15. It will now be evident that when the valve plunger 88 is in one position, such as that shown in Figure 5, the pressure port 94 is connected to channel 98 and the valve plunger 86 is shifted 70 to the right; and when the port 94 is connected to channel 99, the plunger 86 is shifted to the left.

As shown in Figure 4, the valve plunger 88 is provided with a detent mechanism comprising 75

a spring pressed detent member 103 which is adapted to alternately engage V-shaped grooves 104 formed in the periphery of the plunger. This plunger is shifted by a pair of dogs 105 and 106 by engagement with beveled surfaces 107 and 108 respectively formed on opposite sides of an enlarged head 109 integral with the valve plunger. The dog 106 is carried by the locking lever 41, as shown in Figure 3, and the dog 105 is carried on the under side of the table being adjustably mounted in a T-slot 110 and clamped in position by a T-bolt 111.

A start and stop valve 112 is provided in the main circuit, and it has a valve plunger 113 which may be manually shifted to any one of three positions, the central position being a stop position. The valve is also hydraulically shifted from its start or normally running position to its stop position by hydraulic means controlled by a pilot valve 114. This pilot valve has a plunger 115, the beveled end 116 of which is engageable by a latch dog 117 during upward movement of the ram for shifting the plunger to the right, and thereby into a position to cause hydraulic shifting of the valve plunger to a stop position. This is accomplished in the following manner.

The valve 114 has a pressure port 118 which is supplied by pump 67; a second port 119 which is connected by channel 120 to the left end of valve 112; a third port 121 which is connected by branch 122 to the return channel 75; and a fourth port 123 which is connected by channel 124 to port 125 of the stop valve 112, which port is positioned such a distance from the end of the valve that after admission of fluid pressure to channel 120, and movement of plunger 113 into its stop position, the port 125 will open and permit escape of fluid into channel 124 and thereby to the right hand end of pilot valve 114 to cause repositioning of the plunger 115 to the position shown in Figure 5. The repositioning of the plunger 115 will simultaneously close the pressure port 118 and thereby prevent pressure building up in the end of valve housing 112 to such an extent that it will cause further movement of the plunger 113.

To insure proper positioning of the plunger 115, a spring pressed detent 126 is provided which is adapted to engage V-shaped notches 127 formed in the periphery of the plunger. It will now be apparent that when the plunger 115 is shifted toward the right the annular groove 128 will disconnect the exhaust port 121 from port 119, and connect the latter to pressure port 118 whereby fluid will flow to shift the stop valve to a stop position, and the continued flow of the fluid into the right hand end of valve 114 will immediately cause repositioning of the plunger 115 and close the pressure port 118. Although it would seem that this cycle of action would take place in such a short period of time that the plunger would re-engage the end of the trip dog, it is desired to point out that the pump 67 has a sufficiently small displacement that an appreciable period of time is necessary before this action is completed and in addition, the ram has a certain amount of coast so that no interference actually occurs. It will be noted that the entire supply of fluid for the pilot circuits is delivered by the pump 67 and since this pump has a constant displacement per unit of time it can readily be determined just what period of time will be consumed in shifting any one of the many control valves.

The main operating circuit which controls the

flow of fluid to the ram and table cylinders is supplied with fluid pressure from an independent pump 129. This pump has an intake 130 through which fluid is drawn from the reservoir 131, and a delivery channel 132 through which fluid is delivered to annular groove 133 formed in the relief valve 134. A channel 135 connects the pump to a pair of pressure ports 136 and 137 of the stop valve. This valve has an annular groove 138, which, in the normal running position of the valve, connects pressure port 136 to port 139, connected by channel 140 to pressure port 141 of the table controlled valve 60. The circuit, as shown, is conditioned to cause downward movement of the broaching ram which means that the table controlled valve plunger 86 is in its right hand position whereby an annular groove 142 connects the pressure port 141 to port 143 which is connected by channel 144 to port 145 of the ram controlled valve 26.

The plunger 61 of this valve is also in its right hand position whereby the port 145 is connected by annular groove 146 to port 23 whereby the pressure fluid will flow through channel 22 to the lower chamber 21 of the ram cylinder and cause downward movement of the ram. The fluid returning through channel 24 to port 25 is directed by annular groove 147 in valve plunger 161, to port 148 and connected channel 149. The latter terminates in port 150 of the table controlled valve 60, which port is connected by annular groove 151 to port 152 and channel 153. The latter terminates in port 154 of the stop valve which at this time is connected by annular groove 155 in the stop valve plunger to channel 156 which terminates in port 157 of a low pressure relief valve 158. The relief valve has a plunger 159 on which is formed a spool portion movable relative to port 157, and, in which is drilled a radial passage 160 intersecting an axial bore 161 in the end of which is fitted a plunger 162.

This plunger terminates in an enlarged head located beyond one end of the plunger 159, and this head acts as a spacer between the end of the plunger and a fixed abutment 163, and the parts are normally held in this position by a spring 164 acting on the opposite end of plunger 159. The fluid returning through channel 156 passes through the radial and axial bores 160 and 161 creating sufficient pressure to cause shifting of the valve plunger 159 to the left thereby uncovering port 157 and permitting fluid to escape past the tapered end 165 of the valve spool to the exhaust port 166 whereby the fluid can return through channel 167 to reservoir.

Attention is invited to the fact that when the plunger 159 is shifted to the left, some of the escaping fluid will be drawn through branch 168 and check valve 169 into the space 170. When the pressure in the axial bore 161 drops and the spring 164 shifts the plunger toward the right, the fluid in the space 170 is put under pressure and retards this movement. This fluid must be forced through the hydraulic resistance 171 to reservoir in order that the return movement of the plunger 159 may take place, and the amount of time will be determined by the value of the resistance. This resistance is sufficiently high to cause the valve plunger 159 to be a fast opening and slow closing relief valve.

The broaching ram continues its downward stroke until the trip dog 83 shifts the plunger 63 of pilot valve 62 to the left which thereby will connect pressure port 66 to channel 72 and cause shifting of valve plunger 61 to its left hand

position. In this new position, the annular groove 126 will connect port 23 to port 172 which is connected by channel 173 to port 174 of the table controlled valve. Since this last named port is closed, return flow from the ram cylinder will not take place.

The annular groove 147 interconnects ports 145 and 148 whereby the pressure fluid entering port 145 will be directed into channel 149 and its branch 175. The branch 175 terminates in port 176 which is now connected by annular groove 177 to port 57, whereby the pressure fluid will flow to the right hand chamber 36 of the table cylinder. The other end of the cylinder is connected through channel 54 to the exhaust port 178 of the ram controlled valve by annular groove 179 which intercouples port 178 with port 58. Port 25 through which fluid pressure was being supplied to the lower end of the ram cylinder is now connected by annular groove 180 to port 181 which is connected by channel 182 to port 183 of the table controlled valve. This last named port is closed and therefore no movement of the ram will take place.

25 It will be noted that the fluid pressure which was being supplied to port 145, is now directed to the table cylinder; and the opposite end of that cylinder is connected to reservoir whereupon the table will be retracted from a cutting position. 30 At the end of the table stroke, the dog 105 will shift the pilot valve plunger 88 and connect pressure port 94 to channel 99 and thereby shift the table controlled valve plunger 86 into its left hand position. This will cause the pressure port 141 to 35 be disconnected from port 143 and connected to port 183, and at the same time, will position the annular groove 184 so as to interconnect port 174 with exhaust port 185. Since port 183 is now connected through valve 26 to the upper end of 40 the ram cylinder and the lower end of the ram cylinder is connected to reservoir, the ram will start its upward movement.

When the ram has nearly completed its upward stroke, the latch dog 111 shifts the pilot valve plunger 115 to the right thereby connecting pressure port 118 to the left hand end of the stop valve, shifting the plunger 113 thereof into a stop position in the manner previously described. This causes the annular groove 138 to interconnect the pressure port 136 of the stop valve to the return port 186 whereby the pump 129 becomes short-circuited to reservoir. At the same time the spools 187, 188 and 189 of the plunger 113 will close ports 139, 137 and 190 respectively. 55 This will prevent escape of hydraulic fluid from the system so that when the pump is reconnected, no voids or spaces will have to be filled before the machine starts operating again.

With the table retracted and the broach near 60 the upper end of its stroke, the operator reloads the work fixture with a new work piece or pieces and then manually throws the stop valve into its starting or running position. This reconnects the pump 129 to port 139 and the ram will continue its upward stroke until a trip dog 85 shifts the pilot valve plunger 63 to the left. This will now shift the ram controlled valve plunger into its right hand position while the table controlled valve plunger 86 is still in its left hand position. 65 Fluid pressure which is still being delivered to port 181 at this time is now connected through annular groove 180 to port 58 and thereby through channel 54 to the left hand end of table cylinder 28 causing the same to advance to a cutting position, and since ports 143 and 150 are

closed, no movement of the broaching ram will take place. Return fluid from the chamber 36 of the table cylinder will pass through channel 53, port 176, annular groove 179 and port 178 to the return channel 191 which is connected at this time through port 192 of the stop valve, annular groove 193 and port 186 to the return channel 168.

After the table completes its advancing movement, the locking lever 41, as it moves into locking position, causes the dog 106 carried thereby to shift the pilot valve plunger 88 to its right hand position, as shown in Figure 5, whereby fluid will be admitted to the left hand end of the table controlled valve and shift the plunger thereof into its right hand position. This will disconnect the pressure port 141 from port 181 of the ram controlled valve and connect it to port 145 thereof, whereby fluid will now be delivered through channel 22 to the lower end of the ram cylinder causing downward movement thereof. The cycle now repeats itself.

If it is possible for the operator to reload the work fixture during the time that the ram is moving upward on its return stroke, the stop dog 117 can be eliminated, whereby the machine will operate continuously.

For set-up purposes and the like the stop valve plunger 113 may be manually moved to a reverse position which will thereby connect the pressure port 137 to port 154 and connect port 139 to a return port 194 whereby the flow in channels 140 and 153 will be reversed and reversal in the movement of the parts will take place.

There has thus been provided an improved 3 broaching machine having improved automatic means for positioning a work piece with respect to a broaching tool and which is simple in construction and operation.

What is claimed is:

1. In a broaching machine having a broaching ram and a work table, the combination of hydraulic means for shifting the table to a cutting position relative to the ram, means for positively stopping the table in said position and thereby causing a reaction on said hydraulic means, and means responsive to said reaction and positionable thereby to prevent return movement of the table during the cutting operation.

2. In a broaching machine having a reciprocating broaching ram and a work table, the combination of fluid operable means for shifting the table toward the ram, a positive stop for limiting said movement, means to lock the table against said positive stop, including a member yieldable to the reaction on said hydraulic means caused by engagement of the table with said stop, and a table locking member responsive to movement of said yieldable member.

3. In a broaching machine, the combination of a broaching ram having a cutting tool attached thereto, a support, a reciprocable work table mounted thereon, a pair of fluid pressure separable parts for causing movement of the table, one of said parts being fixed to the table and the other carried by the support, a positive stop for limiting movement of the table toward the ram, and thereby acting as an abutment for one of said parts, means effective upon engagement with said stop to release the other part for movement by the fluid pressure, and means responsive to said movement to lock the table against said positive stop.

4. In a broaching machine having a broaching ram, a support and a work table movable on

the support from a loading position to a cutting position, the combination of means for moving the table from one position to the other, including a pair of cooperating parts adapted to be separated by fluid pressure, one of said parts being attached to the table, means to mount the other part on the table support, a swinging lever operatively connected to the last named part, means to supply fluid pressure to cause separation of said parts, means to prevent rotation of said lever to thereby cause movement of the table, and means operable upon completion of table movement to release said swinging lever whereby continued action of said fluid pressure will cause said lever to lock the table.

5. In a broaching machine having a broaching ram and a reciprocable work table movable relative thereto, the combination of means for effecting said movement, including a piston and cylinder, one of which is attached to the table, a support for the other member, a lost motion connection between the last named parts, a table locking lever operatively connected to said last named member whereby upon admission of pressure to one end of said cylinder the table will be moved and then the lever, and upon admission of pressure to the other end the lever will be moved and then the table.

6. In a broaching machine having a fluid operable broaching ram and a work table movable to and from a cutting position with respect to said ram, the combination of power operable means for moving the table to a cutting position, a locking lever for positively holding the table in the cutting position, a source of fluid pressure for causing reciprocation of the ram, a control valve, a pilot circuit, including a pilot valve for controlling the shifting of said control valve, and means trip operable by the locking lever during movement into table holding position for shifting said pilot valve into a position that will cause said main control valve to assume a position that will connect said fluid pressure for operation of said ram.

45. 7. In a broaching machine having a broaching ram and a work table, the combination of fluid operable means for shifting the ram and the table respectively, a main control circuit including a source of fluid pressure, valve means for alternately connecting said source to said fluid operable means, an independent pilot circuit for effecting fluid shifting of said valve means, including a metering pump and individual pilot valves associated respectively with the ram and the table, means for tripping said pilot valves from the moving supports, said metering pump being of sufficiently small volume whereby a slight delay occurs between tripping of said pilot valves and the shifting of said valve means whereby the moving supports may complete their movement before the next action takes place.

8. In a machine tool having a reciprocating slide, the combination of fluid operable means for shifting said slide, a source of fluid pressure therefor, a stop valve, a pilot circuit for shifting said stop valve from a running position to a stop position, including trip operable means for connecting fluid pressure to said pilot circuit, and means to utilize said fluid pressure after the stop valve has been shifted to cause repositioning of the trip operable means.

9. In a machine tool having a fluid operable slide and fluid pressure means for actuating said slide, the combination with a stop valve interposed between said fluid operable means and

said fluid pressure means, of a trip plunger, means carried by the slide for shifting said plunger, power means operable by said plunger for causing shifting of said stop valve, and means responsive to completion of the shifting movement of said stop valve to automatically reposition said trip plunger.

10. In a machine tool having a fluid operable ram, a source of fluid pressure, and a valve for controlling the coupling of said fluid pressure to the ram, the combination of a fluid operable pilot circuit for shifting said valve from one position to another, manually operable means for shifting said valve, and means to automatically release the fluid after effecting a shifting of the valve and thereby condition the valve for immediate manual operation.

11. In a machine tool having a work support and a tool support, the combination with power operable means for effecting relative movement between the supports, of a stop mechanism, fluid pressure means for actuating said stop mechanism, manually operable means for actuating said stop mechanism, and means to automatically release said fluid pressure after actuation of said stop means to thereby reinstate said manual control.

12. In a machine tool having a work support, and a tool support, an hydraulic control circuit for alternately moving said supports, including fluid operable motors for actuating the respective supports, a first control valve having a pair of pressure receiving ports and separate pairs of channels extending to each of said motors, a pilot circuit for controlling the shifting of said valve including trip dogs carried by one of said supports, a second valve for alternately coupling said pressure receiving ports to a source of pressure, a pilot circuit for governing the shifting of said second valve, means trip operable by the other of said slides for controlling said last named pilot circuit, a stop valve, fluid operable means controlled by the first named slide for causing shifting of said stop valve to a stop position, and manually operable means for repositioning said stop valve in a running position.

13. In a broaching machine having a broaching ram and a work support, the combination of means for shifting said work support to a cutting position and locking the same in said position, including a piston and cylinder, the latter being integral with said work support, positive stop means for determining the cutting position of said table, a piston rod integrally connected to said piston and supported for limited axial movement, a bell crank having a bifurcated connection with said piston rod, a locking lever, a locking abutment carried by the table, said abutment riding on said locking lever during movement of the table to prevent rotation thereof caused by reaction of the fluid pressure on said piston in moving the table, said lever being of such length that the abutment will clear the end of the lever when the table hits the positive stop whereby the lever may move into endwise engagement with the block to prevent return movement of the table during a cutting operation.

14. A control mechanism for a broach or the like of the type including a support, a broach ram reciprocable on the support and a work holder movable into and out of operative relation with respect to the ram, said control mechanism including a hydraulic circuit for actuation of the

broach ram, an actuation controlling valve therefor, a second hydraulic circuit for effecting movement of the work holder, a locking member actuatable by said circuit for securing the holder in operative position, and means actuatable by movement of the locking member for shifting said valve to initiate movement of the broach ram.

15. A control mechanism for a broach or the like of the type including a support, a broach 10 ram reciprocable on the support and a work holder movable into and out of operative relation with respect to the ram, said control mechanism including a hydraulic circuit for actuation 15 of the broach ram, an actuation controlling valve therefor, a second hydraulic circuit for effecting movement of the work holder, a locking member actuatable by said circuit for securing the holder in operative position, means actuatable by movement 20 of the locking member for shifting said valve to initiate movement of the broach ram, a main control valve effective as respects both of said circuits, a ram controlled hydraulic actuator therefor, means on the ram for effecting one direction of movement of said actuator, and 25 means activated by movement of the valve for effecting reverse shifting of the actuator.

16. In a machine of the character described, the combination with a hydraulically reciprocable broach carrying ram and a work holder 30 movable toward and from the ram, of a reversing valve for determining the alternate directional movements of the holder, cooperating trip elements associated with the ram and valve for effecting reversing positions of the latter, a power 35 circuit controlling valve having stop and actuating positions, an actuation control valve for determining power shifting thereof to stop position and uni-directionally effective trip means associated with the ram and actuation control valve 40 disposed to actuate the latter to shift the main valve into stop position at an intermediate point in the stroke of the ram.

17. In a machine of the character described, the combination with a hydraulically reciprocable broach carrying ram and a work holder 45 movable toward and from the ram, of a reversing valve for determining the alternate directional movements of the holder, cooperating trip elements associated with the ram and valve for

effecting reversing positions of the latter, a power circuit controlling valve having stop and actuating positions, an actuation control valve for determining power shifting thereof to stop position and uni-directionally effective trip means 5 associated with the ram and actuation control valve disposed to actuate the latter to shift the main valve into stop position at an intermediate point in the stroke of the ram, and means controlled by movement of the main valve into 10 stop position for repositioning the trip operated actuation control valve.

18. In a machine of the character described, the combination with a hydraulically reciprocable broach carrying ram and a work holder movable towards and from the ram, of a first piston and cylinder mechanism for actuation of the ram, a second piston and cylinder mechanism for actuation of the work holder, one of said last-named parts being supported for floating movement, a hydraulic circuit for effecting actuation of the respective piston and cylinder mechanisms including a first ram actuatable reversing valve for determining table movements, trip means on the ram for effecting opposite movements of said valve as the ram approaches its limit of movements in either direction, a second valve for determining the reverse movements of the ram, trip means carried by the work holder for effecting actuation of said valve in one direction of movement of the work holder, a work holder locking member coupled with the floating work holder actuating member and shiftable into locking position when the work holder reaches its limit of movement in one direction, means 30 actuatable by movement of the member into locking position for shifting the ram actuation controlling valve, a stop valve effective as respects both ram and work holder, temporarily energizable means for effecting power shifting of said 35 valve to a stop position, and uni-directionally effective actuating means therefor carried by the ram and disposed to actuate the stop valve at an intermediate point in the movement of the ram, substantially as and for the purpose described.
